United States Patent Office

Des. 200,264
Patented Feb. 9, 1965

200,264

TOTE BOX

Melvin Tudor, 333 Old Courthouse Road, New Hyde Park, N.Y., and Leon Novet, 3203 Ocean Harbor Drive, Oceanside, N.Y.

Filed Aug. 8, 1963, Ser. No. 76,148

Term of patent 14 years

(Cl. D58—13)

FIG. 1 is a perspective view of a tote box showing my new design, the sides opposite those shown being substantially similar thereto, and

FIG. 2 is a top view thereof.

We claim:

The ornamental design for a tote box, as shown and described.
